(57) **CLAIM**

The ornamental design for a point and shoot camera wrap, as shown and described.

DESCRIPTION

FIG. 1 is a rear view of a point and shoot camera wrap showing our new design in a wrapped position;

FIG. 2 is a front perspective view of our point and shoot camera wrap in a wrapped position;

FIG. 3 is a top view of our point and shoot camera wrap in a wrapped position;

FIG. 4 is a bottom view of our point and shoot camera wrap in a wrapped position;

FIG. 5 is a left side view of our point and shoot camera wrap in a wrapped position;

FIG. 6 is a right side view of our point and shoot camera wrap in a wrapped position;

FIG. 7 is a top view illustrating the exterior of the point and shoot camera wrap in an unwrapped position; and,

FIG. 8 is a top view illustrating the interior of the point and shoot camera wrap in an unwrapped position.

The strap shown in chain line in FIGS. 1 and 2 and the circular keeper shown in chain line in FIG. 4 form no part of our design. The dash lines in the Figures indicate stitching.
